UNITED STATES PATENT OFFICE.

HOY HOWARD, OF MANSFIELD, OHIO, ASSIGNOR OF ONE-HALF TO J.
DITWILER & SONS, OF SAME PLACE.

BUCKLE.

SPECIFICATION forming part of Letters Patent No. 310,588, dated January 13, 1885.

Application filed November 3, 1884. (No model.)

To all whom it may concern:

Be it known that I, HOY HOWARD, a citizen of the United States of America, residing at Mansfield, in the county of Richland and State of Ohio, have invented certain new and useful Improvements in Buckles, of which the following is a specification, reference being had therein to the accompanying drawings.

My invention relates to that class of barbed buckles which are made of one piece; and it consists in the peculiar construction and arrangement of the parts thereof, as more fully hereinafter described and claimed.

In the accompanying drawings, Figure 1 represents a front elevation of a buckle constructed according to my improvement; Fig. 2, a sectional side view of the same. Fig. 3 is a plan of the blank before being bent into shape.

In making this buckle, a blank of the form shown in Fig. 3 is first provided, which is then bent by appropriate means to form a hook, A, a tongue, B, barbs C, and loops D E, as shown.

To make the loops, the wings F (see Fig. 3) are bent backward, and preferably soldered at their adjacent edges, (see dotted line in Fig. 1,) thus leaving two loops, D E, one above

and the other below the barbs C. Through these loops the material of the suspender is passed, so as to bring the back of it in contact with the points of the barbs, which will catch in it and hold the same fast when the material is pulled in one direction, but will allow it to pass readily in the other direction, as is well understood.

What I claim as new is—

1. A buckle made from a single piece of metal, provided with loops D E, covering the suspender material on both sides, and having the barbs C between them, substantially as described.

2. A barbed buckle, formed from a single flat piece of metal, having the wings D, provided with barbs, formed thereon, and bent to form two loops, one above and the other below the barbs, to receive the suspender-webbing, substantially as described.

In testimony whereof I affix my signature, in presence of two witnesses, this 31st day of October, 1884.

HOY HOWARD.
